US00D911701S

(12) **United States Design Patent** (10) **Patent No.:** **US D911,701 S**
Bestel (45) **Date of Patent:** **** Mar. 2, 2021**

(54) **MOUTH GUARD CLEANING AND STORAGE DEVICE**

(71) Applicant: **Beast Enterprises, LLC**, La Jolla, CA (US)

(72) Inventor: **Khris Bestel**, Boise, ID (US)

(**) Term: **15 Years**

(21) Appl. No.: **29/617,116**

(22) Filed: **Sep. 12, 2017**

Related U.S. Application Data

(63) Continuation of application No. 15/701,665, filed on Sep. 12, 2017, now abandoned.

(51) **LOC (13) Cl.** **03-01**

(52) **U.S. Cl.**

USPC **D3/203.1**

(57) **CLAIM**

The ornamental design for “mouth guard cleaning and storage device”, as shown and described.

DESCRIPTION

FIG. 1 is a bottom perspective view of a mouth guard cleaning and storage device in a closed configuration;

FIG. 2 is a top view thereof;

FIG. 3 is a bottom view thereof;

FIG. 4 is a top perspective view thereof;

FIG. 5 is a top perspective view of the mouth guard cleaning and storage device in an open configuration;

FIG. 6 is an exploded view of the mouth guard cleaning and storage device;

FIG. 7 is a top perspective view of the mouth guard cleaning and storage device in a open configuration and shown in use with environment; and,

FIG. 8 is a top perspective view of the mouth guard cleaning and storage device in a closed configuration and shown in use with environment.

The broken lines depict portions of the article and environment that form no part of the claimed design.

1 Claim, 5 Drawing Sheets
